UNITED STATES PATENT OFFICE.

FREDERICK M. WHYTE, OF TARRYTOWN, NEW YORK, ASSIGNOR TO HUTCHINS CAR ROOFING COMPANY, OF DETROIT, MICHIGAN, A CORPORATION OF MICHIGAN.

UNLOCKING MECHANISM FOR CAR-COUPINGS.

1,162,269.

Specification of Letters Patent. Patented Nov. 30, 1915.

Application filed March 20, 1914. Serial No. 826,015.

To all whom it may concern:

Be it known that I, FREDERICK M. WHYTE, a citizen of the United States of America, residing at Tarrytown, in the county of Westchester and State of New York, have invented certain new and useful Improvements in Unlocking Mechanism for Car-Couplings, of which the following is a specification, reference being had therein to the accompanying drawings.

The invention relates to mechanism for unlocking car couplers, and comprises the novel construction as hereinafter set forth.

In the drawings: Figure 1 is an elevation of the mechanism as applied to the end of a car; Fig. 2 is a plan view thereof; Fig. 3 is a cross section.

A is the coupler locking pin of a car coupler (not shown).

20 B is a rod formed with a crank or laterally-deflected portion C at the outer end thereof, preferably having an operating handle D.

E is a bracket preferably having a rounded arm E' which engages an aperture F near the inner end of the bar B. The outer end of this arm E' is provided with a vertically-extending pivot E² which engages the eye G of a rod H extending into engagement with the pin A. The inner end of the rod B is bent outward to form a laterally-extending arm B' which passes beneath the rod H and forms a support therefor.

J is a bracket which forms a guide for the vertical movement of the bar C, and also a fulcrum for said bar when rotated by the turning of the crank C.

With the construction as described in operation, the locking pin A may be raised by operating the rod C, either as a lever, the outer end of which is depressed, or as a rock-shaft which is rotated by the crank C. In the first operation, the bracket F acts as a fulcrum for both the lever B and the rod H, which together constitute a compound lever, the lateral arm B' lifting the rod H. This movement of the rod H is permitted by making the eye G thereof sufficiently larger than the pin E² to provide for the necessary angular movement, while a cross pin K or other securing device holds the eye G from moving upward. On the other hand, when the crank C is turned the rod B will slide around the curved arm E' of the bracket E,

and this movement will cause the upward movement of the arm B', which will lift the rod H in the same manner. By reason of the fact that the rod H is separate from the rod B, a relative movement of the car coupler and car body is permitted, this being necessary in the ordinary operation of a car coupler draft rigging.

What I claim as my invention is:—

1. An uncoupling device for car couplers, comprising a bar having a laterally-deflected portion at its outer end, an aperture near its inner end, with a laterally-extending portion beyond said aperture, a bracket-arm engaging said aperture and forming a segmental bearing for said bar, and a second bar pivotally attached to said bracket-arm and extending over the laterally-extending portion of said first-mentioned bar, its inner end being in engagement with the locking member of the car coupler, and all so arranged that the inner end of the second-mentioned bar will be raised when the outer end of the first-mentioned bar is depressed or is revolved as a crank.

2. A car coupler unlocking mechanism, comprising a rod having a crank at its outer end and a lateral extension at its inner end, a universal, pivotal fulcrum for said rod, and a second rod engaging said universal pivotal fulcrum at one end, being engaged at its opposite end with the coupler locking member and having an intermediate bearing upon the lateral extension of said first-mentioned rod.

3. A car coupler unlocking mechanism, comprising two rods, a fulcrum member universally, pivotally engaging one of said rods intermediate its end and the other rod at its end, the outer end of the first-mentioned rod bent laterally, and a lateral extension at the inner end thereof having a bearing on the inner side of the second-mentioned rod, and a coupler locking member engaging the opposite end of said second-mentioned rod.

4. A car coupler unlocking mechanism, comprising a rod having an actuating crank at its outer end, a lateral extension at its inner end and an aperture intermediate its ends, a fulcrum bracket having a curved arm passing through the aperture in said rod, and a second rod universally-pivotally connected to said fulcrum member, passing over

the lateral extension of said first-mentioned rod and having its opposite end engaged with the coupler locking member.

5. A car coupler unlocking mechanism, comprising a rod having an actuating crank at its outer end, a lateral extension at its inner end and an aperture intermediate its ends, a bracket having a curved arm passing through said aperture and terminating in a 10 shouldered pin, a second rod having an eye at one end loosely engaging said shouldered pin to form a universal, pivotal connection therewith, said rod passing over the lateral extension of said first-mentioned rod and 15 engaging the coupler locking with its opposite end.

6. A car coupler unlocking mechanism, comprising a rod having laterally deflected

portions at its opposite end and apertured intermediate its ends, a bracket engaging 20 said aperture and permitting the angular movement of said rod thereupon, a second rod resting intermediate its ends upon the laterally deflected portion of said first-mentioned rod and provided with a pivotal support at its inner end upon said bracket permitting of a movement in a horizontal plane independent of said first-mentioned rod, to 25 compel a vertical movement with said rod when either rocked or tilted.

In testimony whereof I affix my signature in presence of two witnesses.

FREDERICK M. WHYTE.
